V. BUCHANAN

CORSET

Filed June 20, 1921

INVENTOR
VITA BUCHANAN.

BY *Conrad A. Detrich*
her ATTORNEY.

UNITED STATES PATENT OFFICE.

VITA BUCHANAN, OF NEW YORK, N. Y.

CORSET.

Application filed June 20, 1921. Serial No. 478,895.

My invention relates to improvements in corsets, and the same has for its object to provide a corset which will fit perfectly, be comfortable to the wearer, and which will give to the person of the wearer a trim and graceful figure.

Further, said invention has for its object to provide a corset which may be readily adjusted in position upon the person of the wearer and snugly embrace the hips, thighs and buttocks.

Further, said invention has for its object to provide a corset whose open front edges may be secured together throughout their entire length and the lower back portion separated at its center and forming two separate seat members.

Further, said invention has for its object to provide a corset comprising a body portion which has the outer appearance of an ordinary corset, and is provided at its lower edge with seat members and means extending inwardly therefrom and adapted to engage the inner edges of the stockings whereby to hold said seat members snugly against the buttocks.

Other objects will in part be obvious and in part be pointed out hereinafter.

To the attainment of the aforesaid objects and ends my invention consists in the novel details of construction, and in the combination, connection and arrangement of parts hereinafter more fully described and then pointed out in the claims.

In the accompanying drawings showing an illustrative embodiment of the invention—

Figure 1 is an illustrative view showing one form of corset constructed according to and embodying my said invention in position upon the wearer;

Fig. 2 is a side view showing one-half or part of the corset spread out, and

Fig. 3 is a detail side view of the lower back portion of the corset showing a modification.

In said drawings 10 designates a corset which, for the purposes of illustrating my invention is herein shown as an open front corset comprising two similarly shaped halves or parts 11 jointly forming a body portion adapted to embrace the waist, hips and seat.

The halves or parts 11 are provided at the upper portions of their rear edges with eyelets 14 to receive one or more laces, as, for

example, 15, for adjustably securing the said rear edges together. The front edge of one of said halves or parts 11 is provided adjacent to its upper portion with studs 16, and below said studs with loops 16', and the front edge of the other of said halves or parts is provided with eyes 17 adapted to engage the studs 16, and below said eyes 17 with hooks 17' registering with the loops 16' of the adjacent edge.

The front edges of the corset halves or parts, whether the same be a high or a low corset, are firmly secured together throughout their entire lengths by the studs 16 and 60 eyes 17, and the hooks and loops 16', 17', while the rear edges of the corset halves or parts are secured together by the lace 15 down to about the end of the spine of the wearer.

The lower rear edge of each half or part is curved downwardly and forwardly towards the lower outer edge of the side of the half or part where the same meets the downwardly and rearwardly curved lower 70 front edge to form a tab or flap 19, to which is secured one end of a stocking supporter 19' adapted to engage, at the outer side of the leg, the upper edge of a stocking.

The lower rear part or seat portion of 85 each half or part is cut away, and to the resulting edges is secured an elastic seat insert 20 which is substantially rectangular in form and preferably made of elastic webbing having its elastic threads 20' extending diagonally from the upper inner end of said insert 20 to its lower outer corner thereof. The outer lower edge 21 of said elastic seat insert is curved at its side in conformity with the lower edge of the corset 95 which meets the tab or flap 19, while the inner edge of said elastic seat insert terminates in a diagonal tapering seat securing or retaining member or strap 22 having a blunt end 23 provided along its edge with a reinforcing strip 24, to which is secured the upper end of a diagonal stocking supporting member 25 having an attaching device 25^a at its lower end adapted to engage the upper edge of the stocking at the inner side of 100 the leg of the wearer.

The upper opposing edges of the rear tapering members or inserts 20 are curved inwardly so that when their free ends are secured to the inner upper edges of the 110 stockings, the said opposing edges will form a more or less rounded or elliptical open

portion 23^a, the purpose of which is obvious.

The construction illustrated in the modification shown at Fig. 3 is essentially like that of the main construction except that in said modification the elastic seat engaging portion 20^a and the stocking supporting member 25' are made in one piece and provided with an adjusting slide 26^a to permit of the adjustment of the attaching device 10 27^a.

It is to be noted that by means of my improved corset construction, the hips, thighs and seat of the wearer are effectively held to shape by the seat embracing portions and 15 by the action of the stocking supporters 19', 25, which tend to draw the sides and the seat portions of the corset taut and thereby efficiently shape and confine the corset about and to the thighs and seat of the wearer.

20 Further, it is to be noted that although I have shown the invention as applied to a corset which is formed of two parts, open at both the front and back, it will be obvious that the invention is equally applicable 25 to corsets which are open either at their front or at their back portions only.

Having thus described my said invention what I claim and desire to secure by Letters Patent is:

30 1. A corset comprising a body portion adapted to be secured together to confine the body of the wearer, and including an elastic seat portion having a free lower edge and means for maintaining the lower edge of 35 the seat portion extended downwardly and forwardly and under tension, substantially as specified.

2. A corset comprising a body portion adapted to be secured together to confine the 40 body of the wearer, and including a seat portion having a free lower edge, and means for maintaining the lower edge of said seat portion extended diagonally, forwardly and downwardly at its central part between the 45 legs of the wearer, substantially as specified.

3. A corset comprising a body portion, adapted to be secured together to confine the body of the wearer, and including a seat portion having a free lower edge, and means 50 secured to said seat portion and adapted for securing to the stockings for maintaining said free lower edge extended downwardly and forwardly between the legs of the wearer, substantially as specified.

55 4. A corset comprising a body portion adapted to be secured together to confine the body of the wearer, and including a seat portion having a free lower edge, and elastic means secured to the seat portion and adapted 60 for securing to the stockings for maintaining said lower rear edge of said seat portion extended downwardly and forwardly between the legs of the wearer, substantially as specified.

65 5. A corset comprising a body portion

adapted to be secured together to confine the body of the wearer, an elastic seat portion therefor having a free lower edge, and means for maintaining a part of the free lower edge of said elastic seat portion extended diagonally downwardly and forwardly between the legs of the wearer, substantially as specified.

6. A corset comprising a body portion adapted to be secured together to confine 75 the body of the wearer, an elastic seat portion therefor having a free lower edge, ends projecting from said seat portion, and means secured to said projecting ends for maintaining a part of said elastic seat portion drawn 80 downwardly and forwardly between the legs of the wearer whereby to conform said elastic seat portion to the buttocks of the wearer, substantially as specified.

7. A corset comprising a body portion adapted to be secured together to confine the body of the wearer, an elastic seat portion comprising two parts having free lower edges and separated at their inner vertical edges, ends projecting downwardly and forwardly from said elastic seat portions, and members each secured at one end to one of said projecting ends and having its other end adapted for attachment to a stocking whereby to hold said elastic seat parts drawn 90 forwardly between the legs, and severally conformed to their respective buttocks, substantially as specified.

8. A corset comprising a body portion adapted to be secured together to confine the body of the wearer, an elastic seat therefor having a free lower edge, and seat retaining members extending downwardly and forwardly from the lower edge of said seat and adapted for securing to a stocking, whereby to maintain said seat portion under tension and conformed to the body of the wearer, substantially as specified.

9. A corset comprising a body portion adapted to be secured together to confine the body of the wearer, a divided seat therefor, and seat retaining members extending diagonally downwardly and forwardly from the adjacent lower edges of said seat and each adapted for securing to a stocking whereby to maintain said seat portion under tension and conformed to the body of the wearer, substantially as specified.

10. A corset comprising a body portion adapted to be secured together to confine the body of the wearer, an elastic seat therefor composed of two parts each having a free lower edge, a seat retaining member extending diagonally downwardly and forwardly from the inner lower edge of each of said elastic seat parts and adapted for securing to a stocking whereby to maintain said seat parts under tension and conformed to the body of the wearer, substantially as specified.

11. A corset comprising a body portion, a pair of substantially rectangular elastic seat portions at the lower rear portion thereof each having a free lower edge, a member extending diagonally downwardly and forwardly from the free corner of each of said seat portions, stocking supporting members extending from said diagonally extending members and in prolongation thereof, and

stocking supporting members secured to the 10 opposite sides of the corset and respectively adapted to engage a stocking at its inner and outer edges, substantially as specified.

Signed at the city of New York, in the county and State of New York, this 13th day 15 of June, one thousand nine hundred and twenty-one.

VITA BUCHANAN.
